UNITED STATES PATENT OFFICE.

MAURICE VERDEGEM AND WILLIAM A. GRAF, OF PATERSON, NEW JERSEY.

SHUTTLE.

Application filed February 27, 1928. Serial No. 257,137.

This invention relates to shuttles and particularly to shuttles used in weaving silk and other fine filaments, in which the filling or weft tension means is required not simply to impose a drag on the filling but to take up any slack that may otherwise result as an incident of the action of the shuttle and the nature of the filling, so that for this purpose the tension means comprises members coacting to maintain a bend or bends in the filling and one of which at least is yieldable to the filling. The principal object of the invention is to provide a reliable and efficient tension device of this class which is adapted to receive the filling by movement of the latter transversely of itself between the members of the device and which will perform this operation unfailingly when the loom is of the class in which replenishing of the filling package when exhausted is accomplished automatically.

In the drawing,

Fig. 1 is a plan of a shuttle embodying the improved tension means;

Fig. 2 is a fragmentary side elevation;

Fig. 3 a section on line 3—3, Fig. 1;

Fig. 4 a longitudinal substantially central fragmentary section;

Fig. 5 a fragmentary plan with the overhanging nose omitted;

Fig. 6 an underneath plan of said nose; and

Fig. 7 a section on line 7—7, Fig. 1.

The shuttle body 1 has the usual opening 2 for the filling package 3 whose quill 4 is supported in some well known way so that when the package is exhausted the empty quill may be automatically expelled downward from the cavity and a fresh or full package substituted. This operation occurs as usual when the shuttle is in the shuttle box which in the present example would be at its right in Fig. 1.

Opening 2 has an extension 5 between it and the right hand end of the body which forms a cavity in the latter open at the top and this cavity is formed with a lateral notch 6 which at its lower end is elongated, as at 7, and forms the filling outlet of the shuttle. A nose 8 is provided on the shuttle body, projecting to the right and being secured at the near side of cavity 5 in Fig. 1 but extending clear of the opposite side, all in such manner as to permit the filling, on a threading operation and when trailing straight from the shuttle as it moves to the

left, to enter the cavity at the far side of the nose in Fig. 1, and then, on a bight being formed in the filling when the shuttle next passes to the right, to enter the outlet 7 via the slit left at 9.

Where the cavity 5 joins the opening 2 there is preferably a well-known type of filling grip device comprising a housing 10 fitted in the shuttle body and a pair of filling clips 11 therein held against each other by springs 12. When the filling in trailing straight from the shuttle as it passes to the left enters cavity 5 it enters between the clips and becomes gripped thereby.

Between this device and the apex of the nose 8 is arranged the improved tension device comprising two members generally designated 13 and 14 in Fig. 1 and adapted to maintain the received filling normally flexed and one (14) being yieldable to permit it to straighten when tautened; in the example each of these is shown formed of wire. The fixed member is formed with an upright portion 13^a which adjoins the side of the cavity 5 opposite that having outlet 7 and which is spaced from the nose 8 and reaches downward, a portion 13^b inclined downwardly from the lower end of portion 13^a and across the cavity 5, under the nose, a portion 13^c extending downwardly from the lower end of portion 13^b, and a returned end portion 13^d; each of these portions is

preferably duplicated by first rebending the wire on itself and then bending both extremities thereof to form them, and the rebending may be done in such a way as to leave a tang or stub 13^e which may be driven into a hole 15 in the shuttle body to hold member 13 in place. A filling rest is thus formed at 13^b which slopes downwardly and off which at its lower end the filling may fall to be thereupon held normally flexed by the portion 13^c of this member and portions of the other member 14; said portions 13^c are formed with concave seats for the filling, as shown best in Fig. 3, so as to serve as filling guides. The movable member 14 is formed with a pivoting eye 14^a, a short arm 14^b projecting therefrom and a long arm 14^c provided with, in the present case, three substantially parallel portions 14^d each extending lengthwise of the axis of eye 14^a and resulting from bending the wire in two loops lying in the same plane; said member is a lever whose eye 14^a has a bearing on a pin or screw 16 in the bottom of the cavity 5.

100
105
110

so that its portions 14^d stand upright, they being so situated as to alternate with the extremities of the (binary) member 13. These portions 14^d are the filling guides of member 14, and they extend above the filling rest 13^b and have their upper ends bent off toward the portions 13^a of member 13, or away from the side of cavity 5 having outlet 7. Member 14 is normally held, by an elastic 17 connecting it with an adjusting screw 18, with its extremity 14^e bearing against the side of cavity 5 opposite that having outlet 7. At the far side of the nose 8 in Fig. 1 a filling passage 19 is left which may be taken as extending between the portions 13^a of member 13 and said nose (see Fig. 3). The level of outlet 7 is well below this passage.

When the shuttle is fully threaded the filling extends from the quill, between the clips 11, between the guides of the members 13 and 14, under the nose 8 in a bight, and then out at outlet 7; it is retained between the guides due to those 13^c being concave. Consequently the members 13 and 14 act in a well known way to maintain tension on the filling.

The threading is thus effected: When the filling, as in trailing the shuttle on the substitution of a fresh for an exhausted package, is drawn straight to the right it enters passage 19 and between clips 11 and lies upon the rests 13^b. When, thereupon, it is formed in a bight under nose 8 and reaches outlet 7 through slit 9, as when the shuttle now moves back to the right in Fig. 1, it encounters the upper ends of portions 14^d of member 14 and shifts this member to the outlet side of the cavity and then falls to position between guides 13^c and 14^d, thus completing the threading. The filling grip device formed by the clips 11 is not indispensable, but it is desirable; without some such device to hold down the filling once it fully enters the passage 19 it is likely to be whipped out of the passage as it is paid from the package, which at that time has its maximum diameter. Although the component parts of each member are preferably formed of the same piece of material, as wire, it will be understood that as long as there are co-acting means, as 13^c—14^d, to maintain a bend or bends in the filling and

down between which the filling is enterable, one of said means being movable toward and from and elastically urged from one side of said body, and also a rest, as 13^b, for the filling having a guiding surface for the thread inclined downward toward said side and merging into the guiding surface of the other of said means and having the movable one of said means projecting in its normal position across such surface, the invention will be accomplished.

Having thus fully described our invention, what we claim is:

1. In combination, a shuttle body having means to receive and hold a filling package and also having an upwardly open cavity between said means and one end of the shuttle, co-acting means in the cavity to maintain a bend in the filling and down between which the filling is enterable, one such means being movable toward and from and elastically urged from one side of the body, and a rest for the filling arranged in said cavity and having a guiding surface for the filling inclined downwardly toward said side of the body and merging into the guiding surface of the other of said means, said movable one of the co-acting means projecting in its normal position across the rest in sharp angular relation thereto.

2. In combination, a shuttle body having means to receive and hold a filling package and also having an upwardly open cavity between said means and one end of the shuttle, and a filling outlet leading from the cavity to the exterior of the body at one side of the latter, co-acting means in the cavity to maintain a bend in the filling and down between which the filling is enterable, one such means being movable toward and from and elastically urged from said side of the body, and a rest for the filling arranged in said cavity and having a guiding surface for the filling inclined downwardly toward said side of the body and merging into the guiding surface of the other of said means, said movable one of the co-acting means projecting in its normal position across the rest in sharp angular relation thereto.

In testimony whereof we affix our signatures.

MAURICE VERDEGEM.
